UNITED STATES PATENT OFFICE.

AUGUSTUS L. MEROLLE, OF BROOKLYN, NEW YORK, ASSIGNOR TO EMPIRE METAL CAP CO., INC., OF BROOKLYN, NEW YORK, A CORPORATION OF NEW YORK.

RECEPTACLE CLOSURE.

Application filed May 10, 1923. Serial No. 637,930.

To all whom it may concern:

Be it known that I, AUGUSTUS L. MEROLLE, a citizen of the United States, residing at Brooklyn, in the county of Kings and State of New York, have invented certain new and useful Improvements in Receptacle Closures, of which the following is a specification.

This invention relates to a receptacle closure, and an object of the invention is to provide a closure of the simple screw type and in which exceptionally strong and substantial thread elements are provided.

A further and more detailed object is to provide a closure of this type having a wire-edge formed thereon by turning up the material at the bottom of the flange, and said flange being formed with inset thread portions pressed therein and extending downwardly to include portions of said wire-edge so that said wire-edge serves as an efficient reinforcement for said thread portion.

A further object is to provide a closure having a wire-edge as described, portions of said wire-edge being indented to provide inwardly projecting lugs upon the flange for engaging beneath projections of the receptacle, and to form portions of the flange directly above said inset portions of the wire-edge to comprise relatively resilient ribs continuing thread-like from said inset portions of the wire-edge whereby to insure uniform grip of the closure circumferentially of the receptacle.

Other objects and aims of the invention, more or less specific than those referred to above, will be in part obvious and in part pointed out in the course of the following description of the elements, combinations, arrangements of parts and applications of principles, constituting the invention, and the scope of protection contemplated will be indicated in the appended claims.

In the accompanying drawings which are to be taken as a part of this specification, and in which I have shown merely a preferred form of embodiment of the invention:

Figure 1 is a side elevational view of a closure constructed in accordance with this invention, the same being illustrated as applied on to a receptacle and a part of the view being shown in vertical section for the disclosure of detailed construction.

Figure 2 is a detailed sectional view taken substantially upon the plane of line III—III of Figure 1.

Figure 3 is a fragmentary detailed view of a portion of the interior surface of the flange of the closure showing one of the thread portions and:

Figure 4 is a bottom edge view of the parts seen in Figure 3.

Referring to the drawings for describing in detail the construction therein illustrated, the reference character L indicates the receptacle which is of course open at its upper end and which may or may not be provided with an annular outstanding bead thereon spaced downwardly from the upper end of the receptacle. Between the bead and the upper end is provided suitable outstanding threads or projections 2 with which the closure is intended to engage by inter-rotation of said parts in the usual manner.

The reference character G indicates generally the closure device the same being made up of a cover part 3 and an annular marginal flange 4 provided thereon for depending about the exterior of the receptacle. The entire closure is formed from a single piece of sheet metal pressed, or drawn, into shape.

The lower annular edge of the flange is bent upon itself to provide an outstanding wire-edge H. Above this wire-edge the flange is provided with suitable corrugations 5 by which the closure may be gripped for screwing it onto and off of the receptacle.

These corrugations are spaced above the wire-edge so as to leave an expanse of the flange, as indicated 6, for carrying the thread indentations 7.

There may be as many thread indentations circumferentially of the flange as desired. Ordinarily however four are sufficient and it will of course be understood that there is a similar number of the projections 2 formed upon the receptacle.

At the lower ends of each of the thread indentations, that is where said indentations meet the wire-edge H, said wire-edge is bent inwardly to provide inset portions 8 directly in continuation of said thread indentations and serving thereby as a very strong and substantial reinforcement for the lower end of said thread indentations. They also pro-

- vide smooth and attractively rounded terminations of said thread indentations. As a matter of fact, the thread indentations extend from a point above the wire edge in an inclined plane downwardly to and across the wire edge without interruption, the material of the wire edge at the lower ends of the thread indentations being bent bodily inwardly as a part of the thread indentations.
- 10 A most important characteristic to be noted in connection with this structure is that whereas the lower end, or beginning, of each of the thread portions of the closure is relatively strong and rigid, due to the presence of the plurality of thicknesses of metal comprising the reinforcing band or wire-edge H, yet the portion of the thread above the wire-edge, comprising as it does only a single thickness of metal, is relatively weak and resilient and is thereby capable of yielding to a certain and desired extent which will permit the several thread portions to assume uniform grip upon the receptacle when the closure is being rotated 25 relative to the projections 2.

Although the upper portions of the threads are relatively resilient yet they are efficiently held against undue spreading and the like by reason of the presence of the reinforcing band constituted by the wire-edge.

Having thus described my invention, what I claim as new and desire to secure by Letters Patent is:

1. A receptacle closure comprising a cover portion and a flange portion, the material of

the flange being bent upon itself to provide a wire-edge at the lower edge of the flange, the material of the flange being also bent to provide an inclined thread indentation therein, and said wire-edge being bent to provide an indentation standing as a continuation and constituent part of said thread indentation.

2. A receptacle closure comprising a cover portion and a flange portion, a wire edge formed upon said flange portion at the lower edge thereof, thread indentations formed upon the flange portion being relatively resilient above their lower end portions, and said wire edge having indentations therein arranged to constitute the lower ends of said thread indentations and to thereby render said lower ends relatively rigid and unyielding.

3. A receptacle closure comprising a cover portion and a flange portion, the material of the flange portion being bent upon itself to provide a wire edge at the lower edge of the flange portion, the material of the flange portion being also bent to provide a thread indentation therein, and said thread indentation extending longitudinally in an inclined plane from a point spaced above the wire edge downwardly across said wire edge, the material of the wire edge being bent bodily inwardly as a part of the thread indentation.

In testimony whereof I affix my signature.

AUGUSTUS L. MEROLLE.
